(57) **CLAIM**

The ornamental design for an electric roller skate, as shown and described.

DESCRIPTION

FIG. 1 is a perspective view of the electric roller skate showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are included for the purpose of illustrating portions of the electric roller skate that form no part of the claimed design.
